(57) **CLAIM**

The ornamental design for a linear color changer component, as shown and described.

DESCRIPTION

FIG. 1 is a side perspective view of a linear color changer component showing our new design;

FIG. 2 is a top view of a linear color changer component thereof;

FIG. 3 is a rear view of a linear color changer component thereof;

FIG. 4 is a side view of a linear color changer component thereof;

FIG. 5 is a bottom view of a linear color changer component thereof; and,

FIG. 6 is a side view of a linear color changer component thereof.

The broken lines in the FIGS. are directed to environment and form no part of the claimed design.

The claim is directed to only the solid lines edges and none of the surfaces bounded by solid, or broken, lines form a part of the claimed design.
